Application October 30, 1944, Serial No. 561,091

3 Claims. (Cl. 74—128)

1

This invention relates to certain novel and useful improvements in a special tool, broadly classifiable as a ratchet wrench, but also adapted to serve as a tool holder in that it may be employed to accommodate detachable sockets for engaging work parts, or other tools such as are applicable thereto.

More particularly, the invention has reference to a ratchet means wrench in which the ratchet is actuated by remote control from coacting squeeze-type levers imparting movement to longitudinal thrust means interposed between said levers and ratchet means.

An object of the invention is to provide a structure which is regarded as an improvement upon prior patented and marketed wrenches, the chosen embodiment being comparatively simple, easy to manipulate, convenient to handle, capable of many uses, and such in construction that it is comparatively inexpensive to both manufacturer and user.

It is known that most ratchet wrenches now employed require bodily movement of the handle back and forth in a horizontal or other plane. The present invention overcomes this by using pliers-type handles which are simply squeezed together in order to actuate a reciprocatory thrust member, the latter in turn operating pawl and ratchet means.

Other features and advantages will become more readily apparent from the following description and the accompanying illustrative drawings.

In the drawings, wherein like numerals are employed to designate like parts, throughout the same:

Figure 1 is a plan or elevational view of a ratchet wrench constructed in accordance with the principles of the present invention.

Figure 2 is an edge elevational view of the same.

Figure 3 is a view with the removable cover plate detached to expose the novel parts mounted for operation in body beneath said cover plate.

Figure 4 is a longitudinal sectional view on the plane of the line 4—4 of Figure 3, looking in the direction of the arrows.

Figure 5 is a cross section on the plane of the line 5—5 of Figure 3.

Figure 6 is a perspective view of a reciprocatory thrust bar.

Referring now to the drawings by distinguishing reference numerals, it will be seen that the main part body 7 (see Fig. 3) is of elongated form and generally rectangular in cross-sec-

2

tional shape, as seen in Figure 5. The outer end of said body is fashioned to accommodate the journaling and retention means 8 of a ratchet wheel 9 which, as seen in Figure 4, is provided with axial extensions 10 which serve as socket and tool adapters, these having spring-pressed retaining balls 11. Mounted in a suitable depression in the body 7 adjacent the ratchet wheel is a common-type spring-pressed pawl, that is, a pawl 12 pressed against the teeth on the ratchet wheel by a spring 13 (Figure 3). To the right of this, as seen also in Figure 3, is a pocket-like recess 14 to accommodate the ratchet-actuating thrust finger 15. The latter is pivotally mounted on the adjacent end of the reciprocatory thrust rod or bar 16, the latter sliding in a diagonal groove 17 or slideway provided in the base of the body, as shown. The thrust finger 15 is hingedly mounted on the bar 16 and held in place by suitable spring clips 18. A coiled spring 19 is interposed between the finger 15 and bar 16 to press said finger into engagement with the teeth of the ratchet wheel. The thrust or push rod 16 is provided with a lateral abutment 20 riding in a pocket 21 provided therefor, said pocket being provided with a return spring 22 engaging the abutment. The rounded end 23 of the push rod serves as an accommodating cam to coact with the self-adapting auxiliary thrust element 24 also located in the groove 17. Element 24 is slightly tapered or of wedge-shaped form and its smallest end is rounded and seated in an accommodation notch 25 provided in the head 26 of the lever 27. This lever 27 coacts with a fixed lever 28 and said lever 27 is pivoted in overlapping relation, as at 29, in the cavity 30. The cover plate, which assembles and conceals stated parts is indicated at 31 and is of a shape corresponding to the main body 7 and is secured in place by appropriate fastenings 32.

In operation, it is evident that by squeezing the handles or levers 27 and 28 together, the former upon the pivot connection 29, the portion 26 engages the auxiliary thrust element 24 and presses same against the rounded end 23 of the main thrust or push bar 16. The bar 16 moves outwardly against the tension of the spring 22 and exerts actuating pressure against the pivoted thrust finger 15 on the outer end of said rod. This action engages finger 15 with the ratchet teeth and the ratchet wheel is thus turned. The step-by-step movement of the ratchet wheel and accompanying tool-holding members 10 is maintained by the spring-pressed pawl 12. It is obvious that by bodily turning the tool over from

the position seen in Figure 3 to an upside-down position, the rotation of the ratchet is reversed.

It is believed that the construction and assembling of the various parts and the procedures of using the tool, as a unit, will be clear to those skilled in the art to which the invention relates.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. A ratchet wrench of the class described comprising an elongated body of general rectangular cross-sectional form provided in one flat face with a diagonal groove opening through said face, said groove constituting a slideway, a thrust rod of a length less than and mounted for reciprocation in said slideway and disposed flush with said one face, said thrust rod being provided on one side intermediate its ends with a lateral abutment, and said body having a recessed pocket in which said abutment is situated and slidably operable, a return spring confined in said pocket engaging said abutment, toothed ratchet means at the outer end of said body, a pawl mounted on said body and cooperable with the teeth of said ratchet means, a pivoted thrust finger on the outer end of said thrust rod, said finger being located in said groove and being engageable with said teeth, together with a single cover plate fitted against the grooved face of said body and closing and shielding said groove, thrust rod, thrust finger, abutment, return spring, and also coacting with and assisting in holding said ratchet means in place, and handle means at the inner end of said body.

2. A ratchet wrench of the class described comprising an elongated body of general rectangular cross-sectional form provided in one flat face with a diagonal groove opening through said face, said groove constituting a slideway, a thrust rod of a length less than and mounted for reciprocation in said slideway and disposed flush with said one face, said thrust rod being provided on one side, intermediate its ends, with a lateral abutment, and said body having a recessed pocket in which said abutment is situated and slidably operable, a return spring confined in said pocket engaging said abutment, ratchet means at the outer end of said body, a pawl mounted on said body and cooperable with the ratchet teeth, a pivoted thrust finger on the outer end of said thrust rod, said finger being located in said groove

and being engageable with said ratchet teeth, a single plate fitted against the grooved face of said body and closing and shielding said groove, thrust rod, thrust finger, abutment, return spring, and also coacting with and assisting in holding said ratchet means in place, a fixed lever mounted on the inner end of said body and laterally and longitudinally bowed and in a plane with one face of the body, a second longitudinally bowed lever pivotally mounted on the inner end portion of said first-named lever, and an auxiliary, independent thrust element interposed between the pivoted movable end of said pivoted lever and the adjacent shiftable end of said reciprocating rod.

3. A ratchet wrench of the class described comprising an elongated body provided in one face with a groove opening through said face, said groove constituting a slideway, a reciprocable thrust rod of a length less than and mounted for reciprocation in said slideway and disposed flush with said one face, said thrust rod being provided with a lateral abutment and said body having a recessed pocket in which said abutment is slidably operable, a return spring confined in said pocket engaging said abutment, a toothed ratchet wheel mounted for rotation at the outer end of said body, a pawl mounted on said body and cooperable with the teeth on said ratchet wheel, a pivoted thrust finger on the outer end of said thrust rod, said finger being located in said groove and being engageable with said ratchet teeth, a cover plate fitted against the grooved face of said body and enclosing and shielding said groove, thrust rod, thrust finger, abutment, return spring, and also coacting with and assisting in holding said ratchet means in place, a fixed lever mounted on the inner end of said body, a second longitudinally bowed lever pivotally mounted on the inner end portion of said first-named lever, and an auxiliary thrust element interposed between the pivoted movable end of said pivoted lever and the adjacent shiftable end of said thrust rod.

ALONZO V. CAPPS.
